UNITED STATES PATENT OFFICE.

JAMES WELLS, OF NEW ROCHELLE, NEW YORK, ASSIGNOR TO JOHN WHALEN, OF NEW YORK, N. Y.

DESIGN FOR A CLOCK CASE OR COLUMN.

SPECIFICATION forming part of Design No. 27,453, dated August 3, 1897.

Application filed June 23, 1897. Serial No. 641,989. Term of patent 14 years.

To all whom it may concern:

Be it known that I, JAMES WELLS, a citizen of the United States, residing at New Rochelle, county of Westchester, and State of New York, have invented and produced a new and original Design for a Column, Pedestal, or the Like, of which the following is a specification.

My invention relates to columns, pedestals, or the like which may be used to support a cap or other ornamental device on the top; and it consists in the configuration of the parts or the ornamentation thereon, substantially as hereinafter described and shown.

15 In the drawings forming part of this specification, Figure 1 is a side elevation of one side of the column; Fig. 2, a plan view of the extreme top, and Fig. 3 a plan view of the extreme bottom, thereof.

20 The column or pedestal comprises five distinguishing parts or sections 1, 2, 3, 4, and 5, each one of which is substantially square or quadrangular in cross-section, as seen in Figs. 2 and 3, where the top part 1 and the bottom

25 part 5 are shown in plan, and the entire column is hollow.

The base of the column comprises a part 5, surmounted by the part 4 of less diameter, with the interposed beading 6, the part 4 having the superposed beading 7. All of these parts have plain surfaces.

Surmounting the base 4 5 is the superbase 3, surmounted by the corniced transom 8, the corners of the base 3 being provided with pilasters 9, on which are produced animal-heads

30 10, as shown, and between the transom 8 and pilasters, on the face of the base 3, are produced horizontal panels 11. Surrounding the

base 3 is the section 2, quadrangular in cross-section and distinguished by four corner-pilasters 12, having ornamental caps 13, the pilasters having depressed panels 14, longitudinally arranged, the pilasters resting upon the transom 8. The section 2 also comprises the corniced transom 15. Surmounting the pilasters 12 and between the transom 15 and pilasters 12 the exterior face of the section 2 has the panels 16 17 produced thereon. The corners of the transom 15 are ornamented as at 18, and the sides of the transom have shield and wreath relief-work 19 20.

Section 1, which surmounts the section 2, comprises the four pilasters 21, each pilaster having two bracket-caps 22, the top of the section flaring outwardly, as at 23, the lower ends of the pilasters resting upon the transom 15.

On each side of the vertical recessed face 24 of the section 1 is produced a clock-dial 25, and around the dial is produced the corner-brackets 26, ornamented by scroll and wreath work, as shown.

The entire column or pedestal is quadrangular in outline and is cast or produced in one single piece, so as to adapt it to be surmounted by a cap or other ornamental device.

Having described my invention, I claim—

The design for a column, pedestal, or the like, substantially as herein shown and described.

Signed at the city, county, and State of New York this 17th day of June, 1897.

JAMES WELLS.
